SOLVENT EXTRACTION OF MINERAL OILS

Orville L. Polly, Long Beach, and Alva C. Byrns,
Palos Verdes Estates, Calif., assignors to Union
Oil Company of California, Los Angeles, Calif.,
a corporation of California

Application August 14, 1942, Serial No. 454,758.

13 Claims. (Cl. 260—674)

This invention relates to the refining treatment of hydrocarbon fractions and has as one of its objectives removing sulfur compounds from petroleum or coal tar oils and distillates, or raffinates and extracts obtained from such materials by extraction with liquid sulfur dioxide or other solvents common to the art. More specifically, the invention is a process for preferentially extracting sulfur compounds and/or aromatic hydrocarbons from oils which are predominantly olefinic, paraffinic or naphthenic and subsequently recovering the solvent and extracted oil.

The invention is for the fractionation of mineral oil with a new solvent which permits the separation of sulfur compounds and aromatics from olefins, paraffins and naphthenes. The solvent is practically inert chemically and its solvent power is readily controlled by addition or removal of water.

The current art of solvent extraction is toward purifying hydrocarbon oils by the removal of "undesirable" constituents rather than to the resolution of hydrocarbon systems into their typical components with a view to recovering intact the various types of substances separated. Thus it is common practice to treat oils with sulfuric acid. A less drastic treatment may be effected by the use of the lower alkyl sulfonic acids. In either case the extract phase is neither readily nor completely convertible to regenerated solvent and unaltered extract oil. Cracked distillates are particularly susceptible by virtue of their high content of olefins, thiophenes and aromatics which tend to be alkylated, polymerized and sulfonated even at temperatures of 0° C. Thus large losses of solvent and oil occur, and the recovery of valuable sulfur bodies or aromatics is not feasible.

It is clearly an advantage to use a solvent which is practically inert chemically, the solvent power of which can be readily adjusted and which is easily recovered from the extracted oil. We have found that compounds of the general type in which one or more carboxyl groups are substituted for hydrogen in thio-ethers, such as alkyl sulfides or thiophanes, are useful for preparing solvents with the above-mentioned desirable properties. More specifically, we use ethyl thioglycolic acid and/or its homologs, of which

we prefer a mixture resulting from the acid hydrolysis of the reaction product of methyl, ethyl, propyl, butyl and amyl sodiomercaptides with sodium chloroacetate. Such a mixture of sodiomercaptides is usually available as refinery waste-alkali liquors which have been used to remove mercaptans from gasoline distillates.

The ethyl thioglycolic acid which we have produced boils at about 123° C. at 15 mm. pressure and has a specific gravity of 1.148 at 26° C.

The figure accompanying this specification shows a schematic method of carrying out the extraction of mineral oil with our novel solvent.

Referring to the figure, the oil to be extracted is introduced near the bottom of column 1 via line 10. The solvent is introduced near the top of column 1 via line 48. After the solvent passes downwardly through column 1 it dissolves a portion of the oil and eventually the solvent is withdrawn as the extract base via line 18.

The raffinate phase is withdrawn from column 1 via line 11 and is then mixed with hot water introduced through line 12 in mixer 13. From mixer 13 the raffinate to which the hot water has been added passes to separator 2 where it is allowed to separate into two phases. The upper phase comprising chiefly refined raffinate is withdrawn from the system via line 15. The lower phase comprising most of the solvent originally contained in the fraction and the water introduced via line 12 is withdrawn via line 16 and is mixed with the extract phase recovered from column 1 through line 18 in mixer 47. In the event that the raw stock introduced into line 10 is a heavy material, such as lubricating oil, it is sometimes desirable to employ a light diluent to aid in the separation of the solvent from the extract. In this event the mixture from mixer 47 passes via line 21, valve 22 and line 23 into mixer 49 where it is mixed with light diluent, such as petroleum naphtha introduced by line 17. From mixer 49 the mixture passes through line 24 into separator 8. In separator 8 the mixture separates into two phases, the upper phase consists chiefly of extract oil diluted with the light petroleum fraction. This phase is withdrawn from separator 8 through line 25. From the bottom of separator 8 an aqueous solution of the ethyl thioglycolic acid is withdrawn

through line 26, valve 27 and line 28 and then passed via line 29 into still 3. By the aid of steam introduced into still 3 the extract oil and water are then passed overhead as a distillate through line 31 into condenser 32 where these vapors are condensed and passed as liquids into separator 4. From the bottom of separator 4 the water is withdrawn through line 34 and discarded. From the top of separator 4 the extract oil is withdrawn through line 33 and then may either be withdrawn completely from the system via line 35 or, as an alternative, may be passed by line 36, valve 37 and line 38 to reactor 6 where it is mixed with a concentrated aqueous solution of an alkali, such as sodium hydroxide, containing some sodium alkyl thioglycolate, to extract the mercaptans present in the oil. The addition of sodium hydroxide to the oil containing the mercaptans forms sodium mercaptide which remains in the aqueous layer. The extract oil free from the mercaptans may be withdrawn via line 39 and the aqueous sodium mercaptide may then be heated with steam and reacted with sodium chloroacetate to form sodium alkyl thioglycolates according to the reaction:

The aqueous solution of sodium alkyl thioglycolates in reactor 6 may be withdrawn through line 40, valve 41 and line 42 from the system or, as an alternative, this aqueous solution may be diverted through valve 44, line 43 into mixer 45 where it is mixed with sulfuric acid and then passed through separator 7. In the bottom of separator 7 an aqueous solution of sodium sulfate is withdrawn through line 46 and is discarded. The top layer in separator 7, which is largely alkyl thioglycolic acid and contains some water, is passed through line 29 into still 3 where the water is distilled off through line 31.

The substituted thioglycolic acid recovered as the bottom fraction in still 3 is withdrawn therefrom through line 30 and is passed through cooler 5 and thence through line 48 back to the extraction column.

In the above description of the process we have described the auxiliary diluent introduced via line 17 into the mixture of extract oil and solvent in order to obtain optimum separation between the oil layer and the aqueous layer in separator 8. In many instances it is unnecessary to use the auxiliary diluent to obtain proper phase separation between the water and the extract oil and, in those cases we simply close valves 22 and 27 and open valve 20 to permit the mixture in mixer 47 to flow via line 19, valve 20 and line 29 directly into still 3 where the solvent is separated from the extract oil in the manner described above.

Obviously, the extract oils or the raffinates may be subjected to a second stage of extraction by a repetition of the procedure we have outlined, by employing the solvent at the same or different concentrations.

The strength of acid employed as solvent will vary with the particular nature of the stock to be extracted. For example, it may be desirable to separate thiophenes from aromatics. We have found this to be possible with our method, but such a separation is more difficult than the separation of thiophenes or aromatics from olefins. In the former case we employ a relatively dilute acid. In any event the acid concentration used would not be below 40% by volume,

with a preferred range of 50% to 90% acid by volume. In some cases it will be useful to incorporate a third component in the aqueous acid employed as solvent. Thus we may use a polar substance mutually soluble in both the water and alkyl thioglycolic acid, as for example only, ethylene glycol or the sulfone of our substituted mercaptoacetic acid, in order to modify the selectivity of the solvent. Such addition imposes no limitations on the procedure already proposed for operating our process.

As would be anticipated, lowering the operating temperature improves the selectivity of our solvent. However, since the selectivity is readily adjusted by varying the acid concentration we prefer to operate the process simply at atmospheric temperature but we do not wish to imply any restriction to such temperature of operation. For example, where the extraction is being applied to a wet stock, such as a gas oil distillate, it may be found advantageous to operate at a somewhat higher temperature than atmospheric, to offset the effect of dilution of the solvent. On the other hand, conditions may obtain where it is desired to employ substantially anhydrous alkyl thioglycolic acid at a temperature sufficiently low to produce phase separation.

The action of this solvent, when applied to the treatment of olefinic gasolines, is illustrated by the following examples, which in themselves are not intended to delineate or limit the general application of our process in any way.

EXAMPLE 1

A 100 ml. sample of cracked gasoline of 51.3° API and containing 3.46% sulfur was agitated two minutes with 50 ml. of a mixture of 80% ethyl thioglycolic acid in water at room temperature (about 70° F.) and allowed to settle two minutes. The extract was drawn off, treated with water, and the extract oil recovered.

A second 100 ml. sample was treated twice consecutively with 50 ml. of 80% acid, as outlined above.

A third 100 ml. sample was treated three times with 50 ml. portions of 80% acid, as above. The raffinates from each run were washed with water until neutral and analyzed for sulfur. The results are presented in the following table:

Table I

	Volume of solvent percent of oil volume	Volume percent yield of raffinate	Weight percent sulfur in raffinate	Weight percent sulfur extracted
55	0		3.46	
60	50	97.5	3.15	11.6
	100	93.0	3.0	19.8
	150	91.5	2.47	35.4

The raffinates were improved in color and odor.

EXAMPLE 2

A series of batchwise extractions similar to those above were made with 100 ml. of a heavier cracked distillate of 41.2° A. P. I. gravity containing 3.6% sulfur. At the end of the sixth stage, using 50 ml. of 80% ethyl thioglycolic acid at each stage, the sulfur content of the washed raffinate was 2.57%, 21.5% of the oil had been removed as extract, for which an analysis showed 10.6 weight percent sulfur.

EXAMPLE 3

The specificity of the solvent is shown by the percentage increase above the original volume of solvent when the solvent is shaken with an equal volume of a 20% blend of the indicated substance in hexane. The results are tabulated below:

Table II

	Acid concentration percent ethyl thioglycolic acid in water			
	84	91	95	98
Percent increase in volume of solvent layer				
2,5-dimethyl thiophene	8	16	26	100
Crude xylene	8	14	24	100
C ₆ thiophene	8	13	20	60
Di-isobutylene	4	8	12	22
Methyl cyclohexane	2	8	12	20
Pure hexane	4	8	10	20

The solubilities of the above substance fall into two well defined classes; thiophenes, thiophanes and aromatics, versus olefins, naphthenes and paraffins at each concentration of solvent. Greater specificity is shown by the more dilute solvents.

The invention may then be described as residing in the use of a novel solvent for the separation of oil into fractions. More specifically, the invention may be stated as residing in the use of a mercapto-substituted carboxylic acid containing one or more carboxyl groups, as for example, the compound may be a mercapto-substituted mono carboxylic acid, such as butyric or propionic acid or it may be a mercapto-substituted poly carboxylic acid, such as succinic acid or adipic acid.

Furthermore, while we have specifically shown that ethyl thioglycolic acid and its homologs, methyl propyl, butyl and amyl thioglycolic acids or mixtures thereof, may be used, it is to be understood that we may also use thioglycolic acids in which the alkyl group specified above may be substituted by aryl groups or aralkyl groups.

Our invention also embraces mercapto-substituted carboxylic acids of the following type:

Where X₁ and X₂ are alkyl groups, unsaturated radicals derived from alkyl groups by loss of hydrogen, aralkyl groups, hydrogen, carbocyclic rings, heterocyclic rings or RS groups the same or different from the RS— groups shown and where R represents an alkyl, aralkyl, carbocyclic or heterocyclic group, or an unsaturated radical derived from an alkyl group by loss of hydrogen and Y represents (CH₂)_n where n=0 or an integer which may be as high as 5 or higher.

As a further modification of our invention we may add other materials to the alkyl thioglycolic acids to increase their selectivity, in addition to those disclosed above. A particularly suitable class of addition compounds to be used is the salts of the substituted thioglycolic acids themselves. These salts may be obtained by partially neutralizing the substituted thioglycolic acid with the desired proportion of a suitable base, and may be used in conjunction with the previously disclosed modifying agents, such as water. The bases which are suitable will include those of

the alkali metals, ammonia, or organic bases, such as the amines, di-amines, ethanolamines, pyridine, morpholine, etc., which are capable of producing salts. The advantages to be gained by the use of salts as addition agents is particularly marked when it is desired to produce substantially pure aromatic hydrocarbons. Various hydrocarbon distillates are available which may be fractionally distilled into a narrow boiling range such that only one aromatic hydrocarbon is present to any great extent. Then by selective solvent extraction by means of our improved process it is possible to obtain the desired aromatic hydrocarbon in any desired degree of purity without the necessity for such auxiliary purifying methods as azeotropic distillation. In a similar way our improved process may be employed in the extraction of narrow distillates containing thiophenes.

For example, in the extraction of toluene from a substrate oil of low aromatic content, such as gasoline raffinate, aqueous ethyl mercaptoacetic acid does not permit the concentration of toluene beyond 80% by volume of the total oil in the extract layer. Above this concentration the system consists of only one phase. Therefore it is not possible to make pure toluene by extraction using aqueous ethyl mercaptoacetic acid. However, the addition of 20% by weight of ammonium ethyl mercaptoacetate to the aqueous mercapto acid produces a new solvent which is capable of producing toluene of better than 90% purity. This is shown by the data in the following tables, giving distribution ratios for single stage extractions:

A. Single stage extraction of toluene from gasoline raffinate (a) with a solvent consisting of 60 weight percent ethyl mercaptoacetic acid, 20 weight percent ammonium ethyl mercaptoacetate, 20 weight percent water:

Percent toluene feed	Raffinate oil	Extract oil
20.0	15.6	52.7
50.0	46.0	75.0
80.0	77.2	87.7
90.0	88.0	93.5

B. Single stage extraction of toluene from gasoline raffinate¹ with a solvent consisting of 80

¹ The gasoline raffinate was obtained by low temperature sulfur dioxide extraction of a California straight run gasoline.

weight percent ethyl mercaptoacetic acid, 20 weight percent water:

Percent toluene feed	Raffinate oil	Extract oil
20.0	15.3	46.3
50.0	43.2	73.6
80.0	76.0	88.5
90.0	(2)	—

² Single phase system.

Other modifying agents as well as ammonia, such as urea, morpholine, aniline may be added to the mercapto-substituted carboxylic acids to secure the desired result. These agents will be recognized as basic substances capable of combining with mercapto-substituted carboxylic acids to form salts, which category may also be extended to inorganic bases, such as sodium or potassium hydroxides, as disclosed above.

Such modifying agents at the same time increase the specificity of the solvent. For example, in the extraction of butene-2 from other

C₄ hydrocarbons the urea salt may be used in conjunction with ethyl mercaptoacetic acid either with or without the addition of water. The following table lists the solubilities of butene-2 and butane in anhydrous ethyl mercaptoacetic acid with and without the addition of urea salt. The measurements were made under comparable conditions.

C ₄ hydrocarbon	Solubility-ml./ml. solvent	
	Ethyl mercaptoacetic acid	Ethyl mercaptoacetic acid+0.15 mols urea
Butene-2	28.9	24.5
Butane	13.3	8.5

Butadiene is similar to butene-2 in its solubility characteristics with these solvents.

The above is simply descriptive of the scope of our invention and is not to be understood as limiting the novel process and solvent which we have discovered.

This case is a continuation in part of our co-pending application, Serial No. 393,188, filed May 13, 1941, now Patent No. 2,347,432.

We claim:

1. A process for the separation of a hydrocarbon mixture into fractions of different types which comprises extracting said mixture with a selective solvent comprising a thioether in which at least one carboxylic acid group is substituted for a hydrogen atom, and a salt of said substituted thioether as a solvent modifying agent, thereby forming a raffinate phase and an extract phase, and separating said phases.

2. A process for the separation of a hydrocarbon mixture into fractions of different types which comprises extracting said mixture with a selective solvent thereby forming a raffinate phase and an extract phase and separating said phases, said selective solvent comprising a carboxylic acid and a salt of said carboxylic acid, said carboxylic acid having the general formula

where X₁ and X₂ are alkyl groups, unsaturated radicals derived from alkyl groups by loss of hydrogen, aralkyl groups, hydrogen, carbocyclic rings, heterocyclic rings or RS groups the same or different from the RS group shown and where R represents an alkyl, aralkyl, carbocyclic or heterocyclic group, or an unsaturated radical derived from an alkyl group by loss of hydrogen, and Y represents (CH₂)_n where n=0 or an integer.

3. A process according to claim 2 in which n is less than 3 and R is an alkyl group containing between 1 and 5 carbon atoms.

4. A process according to claim 2 in which the salt of the carboxylic acid is an organic amine salt.

5. A process according to claim 2 in which the salt of the carboxylic acid is an alkali metal salt.

6. A process according to claim 2 in which the hydrocarbon mixture also contains organic sulfur compounds and these are extracted by the selective solvent.

7. A process according to claim 2 in which the hydrocarbon mixture contains aromatic type hydrocarbons and these are extracted by the selective solvent.

8. A process for the separation of a hydrocarbon mixture into fractions of different types which comprises extracting said mixture with S-ethyl mercaptoacetic acid and ammonium S-ethyl mercaptoacetate.

9. A process as claimed in claim 8 in which water is added to the extraction agents.

10. A process for the separation of a hydrocarbon mixture into fractions of different types which comprises extracting said mixture with S-ethyl mercaptoacetic acid and a urea salt thereof.

11. A process for the extraction of toluene from a hydrocarbon mixture containing toluene and non-aromatic hydrocarbons which comprises commingling said hydrocarbon mixture with a selective solvent comprising S-ethyl mercaptoacetic acid and ammonium S-ethyl mercaptoacetate and thereby forming a raffinate phase comprising hydrocarbon fractions which are insoluble in the said selective solvent and an extract phase containing the toluene dissolved in the said selective solvent and separating said raffinate phase from said extract phase.

12. A process for the recovery of toluene from a hydrocarbon mixture containing toluene and non-aromatic hydrocarbons which comprises contacting said mixture with a solvent comprising S-ethyl mercaptoacetic acid, ammonium S-ethyl mercaptoacetate and water and thereby dissolving the toluene present in said hydrocarbon in said solvent, separating the solvent containing the dissolved toluene from the remaining undissolved hydrocarbons and separating the toluene from the solvent.

13. A process according to claim 12 in which the solvent comprises about 60% by weight of S-ethyl mercaptoacetic acid, 20% by weight of ammonium S-ethyl mercaptoacetate and 20% by weight of water.
